COMBINED SAFETY HELMET AND LAMP

Duane W. Miller, 246 Westfield St., Rochester, N.Y.

Filed July 21, 1964, Ser. No. 80,953

Term of patent 14 years

(Cl. D3—13)

FIG. 1

FIG. 2

FIG. 1 is a front perspective view of a combined safety helmet and lamp, showing my new design;
 FIG. 2 is a rear perspective view thereof.

The sides of the helmet not seen in FIGS. 1 and 2 are substantially the same as the corresponding sides shown in FIGS. 1 and 2.

I claim:

The ornamental design for a combined safety helmet and lamp, substantially as shown and described.
